UNITED STATES PATENT OFFICE.

JOSEPH W. TROHA, OF CLEVELAND, OHIO.

RATCHET TOOL.

Application filed September 20, 1926. Serial No. 136,680.

This invention relates to ratchet tools and has for its object the provision of means designed to give the tool a ratcheting movement.

5 Various other uses of my improvement will suggest themselves to those skilled in the art.

In the accompanying drawings, which illustrate my invention, Figure 1 is a plan 10 view of the tool, with cheek plate removed, showing my invention in operative position when closed.

Figure 2 is a plan view, with cheek plate removed, showing the ratchet mechanism 15 open.

Figure 3 is a plan view of the polygonally shaped ratchet member.

Figure 4 is a side view of Figure 3.

Figure 5 is a sectional view of the tool 20 showing the pivot rivet and the limiting pin.

Figure 6 is a plan view, with cheek plate removed, showing another method of adaptation of the principle involved.

25 Figure 7 is a plan view of a cheek plate. 1 refers to the handle, which is pivotally mounted on the pivot rivet 8 in the cheek plates 2:2'. The handle is manually-biased and closed, being limited in its travel by the 30 limiting pin 8' in the cheek plates and through the instrumentality of an arcuate-shaped or other suitably shaped opening 7 located in the handle. The polygonally shaped ratchet member 3 is provided with 35 integral cylindrical shaped shoulder portions 4:4' and provided with polygonally shaped or other suitable shaped perforation 5 through it for adaptation to bolts, nuts, tools and the like.

40 The portion 6 of the handle, it will be observed, is normally out of the path of the polygonally shaped ratchet member, allowing the handle to be brought into engagement with the ratchet member as shown in 45 Figure 1. 9 refers to the hole or bore in the cheek plate adapted to take the shoulder portion of the ratchet member 3.

In practice, a bolt, nut or tool having a 50 portion corresponding in size to the polygonally shaped or other suitable shaped perforation 5, is inserted in said perforation. The method of rotating the ratchet member 3 is as follows: when the handle 1 is in the closed position a twisting strain can be exerted upon the tool, when manually biased the cheek plates with the handle mounted

therein are free to turn on the ratchet member, when desired position of handle is located the handle is closed the straight end 60 on the handle encountering one of the sides on the polygonally shaped portion of the ratchet member thus alternately holding and releasing the ratchet member. These operations are repeated at will until desired rotation is obtained. When it is desired to reverse the direction of rotation the tool is turned upside down on the object, because the direction of the travel of the handle is limited to one direction. This arrangement 65 prevents wearing away the ratchet member 70 and also the handle, a common defect with the ordinary type of ratchet tool mechanism.

Various changes may be made without departing from the spirit of my invention.

What I claim as new and desire to secure 75 by Letters Patent, is:—

1. A ratchet tool comprising two cheek plates stayed apart each provided with a bore for mounting a ratchet member therein and each also provided with perforations 80 for a pivot rivet and a limiting pin, said ratchet member having a polygonally shaped perforation through it and also having cylindrically shaped shoulder portions and also a polygonally shaped integral intermediate ratchet portion, and being rotated by means of a handle pivotally mounted on the pivot rivet fixedly mounted in the cheek plates and having its travel limited by the limiting pin, the said handle having a 85 straight end portion to coat with a side of the ratchet member also having a concaved portion to provide means for the passage of the corners on the intermediate portion of the ratchet member, the said handle also 90 having an arcuate-shaped opening in it operatively associated with the limiting pin which is also fixedly mounted in the cheek plates and interposed between the ratchet member and the pivot rivet, the said cheek 95 plates, ratchet member and handle being held in assembled position by riveting the pivot rivet and the limiting pin in the cheek plates.

2. A ratchet tool comprising two cheek 105 plates stayed apart each provided with a bore for mounting a ratchet member therein and each also provided with perforations for a pivot rivet and a limiting pin, said member having a polygonal perforation through it 110 and also having cylindrically shaped shoulder portions and also a polygonally shaped

- integral intermediate ratchet portion, and being rotated by means of a handle pivotally mounted on a pivot rivet fixedly mounted in the cheek plates and having its travel limited by the limiting pin, said handle having a straight end portion to coact with a side of the ratchet member also having a concaved portion to provide means for the passage of the corners on the intermediate portion of the ratchet member, said handle also having an arcuate shaped opening in it operatively associated with the limiting pin which is also fixedly mounted in the cheek plates, the pivot rivet interposed between the ratchet member and the limiting pin, said cheek-plates, ratchet member and handle being held in assembled position by riveting the pivot rivet and limiting pin in the cheek plates.
3. A ratchet tool comprising two cheek plates stayed apart each provided with a bore for mounting a ratchet member therein and each also provided with perforations for a pivot rivet and a limiting pin, said ratchet member having a polygonal perforation through it and also having cylindrical shaped shoulder portions and also a polygonally shaped intermediate ratchet portion, and being rotated by means of a handle pivotally mounted on a pivot rivet fixedly mounted in the cheek plates and having its travel limited by the limiting pin, said handle having a straight end portion to coact with a side of the ratchet member and a concaved portion to provide means for the passage of the corners on the intermediate portion of the ratchet member, said handle also having an arcuate shaped opening in it operatively associated with the limiting pin which is fixedly mounted in the cheek plates and interposed between the ratchet member and the pivot rivet, said cheek plates, ratchet member and handle being held in assembled position by riveting the pivot rivet and limiting pin in the cheek plates.
4. A ratchet tool comprising two cheek plates stayed apart, each provided with a bore for mounting a ratchet member therein and each also provided with perforation for a pivot rivet, said ratchet member having a polygonal perforation through it and also having cylindrical shaped shoulder portions and also a polygonally shaped integral intermediate ratchet portion, and being rotated by means of a handle pivotally mount-
- ed on the pivot rivet fixedly mounted in the cheek plates, the said pivot rivet adjacent the ratchet member, the said handle having a straight end portion to coact with sides of the ratchet member and a concaved portion to provide means for the passage of the corners on the intermediate portion of the ratchet member, said cheek plates, ratchet member and handle being held in assembled position by riveting the pivot rivet in the cheek plates.
5. A ratchet tool comprising two cheek plates stayed apart, each provided with a bore for mounting a ratchet member therein and each also provided with perforations for a limiting pin, said ratchet member having a polygonal perforation through it and also a polygonally shaped integral intermediate ratchet portion, and being rotated by means of a handle mounted on the limiting pin, said limiting pin adjacent the ratchet member and fixedly mounted in the cheek plates, said handle having a straight end portion to coact with sides of the ratchet member and a concaved portion to provide means for the passage of the corners on the intermediate portion of the ratchet member, said handle also having an arcuate shaped opening in it operatively associated with the limiting pin, said cheek plates, ratchet member and handle being held in assembled position by riveting the limiting pin in the cheek plates.
6. A ratchet tool comprising two cheek plates stayed apart, each provided with a bore for mounting a ratchet member therein and each also provided with a perforation for a pivot rivet, said ratchet member having a polygonal perforation through it and also having cylindrical shaped shoulder portions and also having a polygonally shaped intermediate ratchet portion, and being rotated by means of a handle pivotally mounted on the pivot rivet fixedly mounted in the cheek plates, said pivot rivet adjacent the ratchet member, said handle having a straight end portion to coact with sides of the ratchet member, and a concaved portion to provide means for the passage of the corners on the intermediate portion of the ratchet member, said cheek plates, ratchet member and handle being held in assembled position by riveting the pivot rivet in the cheek plates.

JOSEPH W. TROHA.
